FURNACE CHUNK BREAKER

Frank J. Boron, Elyria, Ohio, assignor to American Brake Shoe Company, New York, N.Y., a corporation of Delaware

Filed Apr. 11, 1958, Ser. No. 728,010

9 Claims. (Cl. 241—67)

This invention relates to the construction of equipment for a furnace of the kind used to fire ore-bearing material or the like incidental to the processing of such material, and the present invention is concerned in particular with the construction of oscillating shafts that are mounted adjacent the furnace and which are to be provided with discs for breaking up the material processed in and emitting from the furnace.

In one form of furnace installation used to process ore-bearing material and the like, the material which is fired in the furnace is funneled out the bottom of the furnace, and spaced parallel rotating shafts composed of steel are interposed to assist in breaking up the fired material emitting from the furnace so that the material is subdivided prior to falling onto transfer belts. Such shafts are provided with so-called breaker discs composed of steel and secured thereto, and the breaker discs are formed with teeth about the outer peripheries thereof which assist in breaking up the burden much in the manner of oscillatable furnace grates. Heretofore, the discs have been joined directly to the shafts, that is, there is a continuous line contact between the adjacent surfaces of the shafts and the discs, and because of the high temperatures encountered the shafts are arranged for water cooling by directing cooling water through hollow internal areas formed in the shafts which prolongs the life of the shaft and the discs.

For the most part, it is the breaker discs which accomplish the work by crushing the material fed to and emitting from the bottom of the furnace. In more recent years, however, higher and higher temperatures are being resorted to in such furnaces, and it is now recognized that in order for the breaker discs to have an appreciable life it is necessary to compose the breaker discs of expensive heat-resistant alloy. On the other hand, it is desirable to construct the supporting shafts for the breaker discs of steel having good heat conductivity, but steel of course has a quite different coefficient of thermal expansion compared to a heat-resistant alloy such as an alloy composed of 10 to 30% chromium, 5 to 30% nickel, 0.1 to 20% manganese, 0.1 to 0.8% carbon, remainder substantially all iron with a 3% maximum tolerance in silicon. This difference in thermal coefficient characteristics coupled with the water-cooled steel shaft introduces a serious problem insofar as the thermal stressing of the alloy discs is concerned, and it is the primary object of the present invention to enable chunk breaker discs composed of a heat-resistant alloy such as the foregoing to be secured to a water-cooled steel shaft under such circumstances that the likelihood of severe or undue thermal stressing of the alloy discs is greatly reduced.

Thus, in contra-distinction to prior and existent arrangements wherein the breaker discs are secured to the shafts either by a continuous line contact in the nature of a press fit or continuous 360° welds, alloy breaker discs in accordance with the present invention are

2

mounted on the shafts with as little contact as possible between the adjacent surfaces of the shafts and the discs. This is accomplished under the present invention by specific modes of establishing a spaced union between 5 the discs and the shaft, and these are exemplified in all instances by first of all cavitating or hollowing the inner diameter of the discs to afford a U-shaped section defined by spaced apart thin arcuate rims thereby reducing the area of the discs which are immediately adjacent or 10 opposite the outer diameter of the shaft on which the discs are mounted. In order to establish spacing between the narrow rims of the discs and the adjacent surfaces of the shaft, the rims of the disc are of larger inside diameter than the outside diameter of the shaft, and a 15 drive connection of very limited surface contact is established between the discs and the shaft in several different ways as will be described hereinafter. The discs extend about the shaft for 360°, but advantageously each disc can be composed of a plurality of segments with spacing 20 between the adjacent ends of the segments allowing for free contraction and expansion of the discs relative to the shaft in a circumferential sense.

Other and further objects of the present invention will 25 be apparent from the following description and claims and are illustrated in the accompanying drawings which, by way of illustration, show preferred embodiments of the present invention and the principles thereof and what I now consider to be the best mode in which I have contemplated applying those principles. Other embodiments of the invention embodying the same or equivalent principles may be used and structural changes may be made as desired by those skilled in the art without departing from the present invention and the purview of the appended claims.

35 In the drawings:

Fig. 1 is a sectional view of a hopper to be mounted beneath a furnace of the kind mentioned above, and showing end views of a plurality of shafts having breaker 40 discs thereon constructed and arranged in accordance with the present invention.

Figs. 2 and 3 are side views of the shafts shown in end elevation in Fig. 1 and further illustrating constructions contemplated by the present invention;

45 Fig. 4 is a plan view of one form of breaker disc constructed in accordance with the present invention;

Fig. 14 is a sectional view similar to that of Fig. 10 but taken on the line 14—14 of Fig. 15; and

Fig. 15 is a sectional view taken substantially on the line 15—15 of Fig. 14.

70 In Fig. 1 of the drawing there is illustrated at A the area at the bottom of a furnace for heat treating pelletized ore material and the like charged in the furnace the flow

of such material from the furnace (not shown) being conveniently indicated by legend. It will be observed that a pair of hoppers H1 and H2 are in a lower position in the area A and are secured to a relatively large mounting plate 20, the arrangement being such that the lower discharge end of the hoppers are disposed to funnel and discharge the material passing through the hoppers H1 and H2 on to a conveyor or the like. The foregoing arrangement represents known structure in the art, and in order to assure that the material to be discharged by the hoppers is properly broken up prior to deposit thereof on to such conveyors or the like, a plurality of chunk breaker shafts S are arranged in two horizontal tiers above the discharge ends of the hoppers, and breaker discs, generally indicated at D in Fig. 1 and to be described in greater detail hereinafter, are individually joined to the shafts S in spaced relation so as to rotate therewith. The shafts S are supported by bearings (not shown) and each shaft, as shown in Figs. 2 and 3, is formed with an axial groove G in which fits a key carried by the drive means for rotating the shafts S. The discs D are provided with teeth T, Fig. 1 as will be described, and in this manner, the rotating discs tend to crush and break up large chunks of the in-flowing material moving from the furnace in the direction of the hoppers H1 and H2.

The breaker discs D are advantageously arranged in different patterns on the shafts to account for a predetermined optimum crushing or breaking action. Thus, referring to Figs. 2 and 3, two of the shafts S, indicated at S2 and S3, respectively, are so constructed that the shaft S2 carries four discs D, whereas the shaft S3 carries eight such discs. It will be appreciated that what is shown in Figs. 2 and 3 is simply illustrative of the different ways in which the discs D may be mounted on the shafts S to which they are allocated.

In furnaces of the kind under consideration, relatively high temperatures are developed such that the inflow of material in the area A causes severe overheating of the shafts S and then discs D. In order to prolong the life of the shafts S, it has previously been proposed to form the shafts of a hollow construction to enable cooling water to be directed into the interior thereof as indicated by legend in Figs. 2 and 3.

In accordance with the present invention, the discs D all consist of a heat resistant alloy of a relatively expensive nature in comparison to ordinary ferrous metal alloys. Thus, discs of the present invention may be cast of the following:

C	0.10-0.80
Ni	5-30
Cr	10-30
Mn	0.1-20
Si	3% max.
Fe	Balance

The alloy used for the discs D has quite different thermal characteristics in comparison to stainless steel used for the shafts S which, as explained above, are to be water-cooled. Hence it becomes important, especially in view of the initial cost of the alloy discs D, to prolong their life and to assure that there will be no cracking or warpage due to the association of the discs D with the water-cooled shafts S. In accordance with the present invention, the discs D are configured and arranged to have as little peripheral contact as possible with the shafts S while still affording sufficient connection between the shafts S and the discs D to cause the discs D to rotate with the shafts S. Three different embodiments of the present invention from the standpoint of construction of the discs D will be described in detail hereinafter, but in each instance the discs D are of hollow form about their inside diameters so as to provide two annular spaced-apart rims thereby reducing in the first instance the possible area contact between the discs D and the related shaft S. Additionally, the internal di-

ameter of each alloy disc of the present invention is slightly larger than the external diameter of the related shaft S on which such a disc is to be mounted, thereby establishing circumferential spacing between the opposed diameters of the disc D and its related shaft S. Advantageously, in one form of the invention, each disc is made up of a plurality of segments which allow for circumferential expansion and contraction, and the embodiments of the present invention are primarily distinguished one from the other on the basis of the particular manner in which the discs can be joined to the shafts for rotation therewith.

One embodiment of a crusher or chunk breaker disc constructed in accordance with the present invention is illustrated in Figs. 4 to 7 inclusive. Thus, the disc 25, Figs. 4 and 5, is in the form of an annular one-piece part cast from the alloy specified above or one closely akin thereto. The disc 25 has a solid circumferential or annular outer wall 26 from which project a plurality of integrally cast teeth or lugs 27 of solid construction throughout, the teeth 27 in cooperation with like teeth on an opposite shaft as S representing the grinding or breaking elements which account for the desired grinding or breaking action on the material flowing from the furnace into the area A and downward past the shafts as S. The disc 25 is cast to have a pair of spaced-apart side walls or flanges 30 and 31 integral with and projecting radially inwardly from the outer circumferential wall 26, and these flanges terminate in flat annular rims 30R and 31R which define the inside diameter of each disc as 25. The distance separating the outer surfaces of the side walls 30 and 31 is no greater than the maximum width of each tooth 27, but the side walls and their rims 30R and 31R are of narrower axial width than are the teeth 27. In fact the combined width or thickness of the walls 30 and 31 is less than that of a tooth 27 and this accounts for the hollow nature of the disc 25 about its inside diameter.

As shown in Fig. 6, the rims of the disc 25 are to concentrically surround the shaft S but are to be spaced slightly therefrom by having the rims of greater diameter than the outside diameter of the related shaft S. In order that each disc as 25 will rotate with the shaft S, the shaft S is provided with a plurality of elongated rectangular steel keys 35 spaced about the circumference thereof and adapted to fit into correspondingly spaced rectangular slots or openings 37 formed about the inside diameter of each disc 25. The slots 37 are of larger dimensions than the keys 35 so that the fit is somewhat loose as shown in Figs. 6 and 7, and this contributes to the attainment of as little contact as possible between the disc and any part of or on the shaft S to thereby minimize the transfer of heat between the disc and the shaft S.

In assembling the discs 25 on the shaft S, shown in Figs. 6 and 7, the discs 25 will be turned until the key-receiving recesses 37 therein are aligned with the keys 35 on the shaft S, whereupon each disc is slipped into place by being moved axially along the shaft S until its key-receiving openings are related to those keys 35 which define the location of the particular disc 25 on the shaft S. As shown in Fig. 7, the keys 35 are secured in place by weldments.

In order that each disc will be properly held in its selected axial position on the shaft S, retainer lugs 40 and 41, Fig. 7, are welded to the outer end surfaces of the keys 35 after the related discs have been assembled in proper position. The lugs 40 and 41 are to be disposed opposite solid surfaces at the sides of the disc. As shown particularly in Fig. 7, it is preferable to have spacing between the opposed surfaces of such lugs and the side walls 30 and 31 of each disc 25, again contributing to the attainment of as little contact as possible between the discs 25 and parts directly in contact with the shaft S.

Another form of the present invention is illustrated in Figs. 8 to 11, inclusive. In this instance, an alloy breaker disc of annular form is assembled from four segments 50-1, 50-2, 50-3, and 50-4, the relationship being such that when the segments are arranged end-to-end to complete a 360° circle, the adjacent ends thereof are spaced slightly from one another as indicated at SP, and such spacing allows for circumferential expansion of the disc assembly 50 relative to the shaft S, Fig. 11, on which such discs are assembled in complementary segmental form. Each disc segment, illustrated in Fig. 8, is formed with a pair of solid teeth 53 and the inside diameter of each segment is hollowed to provide a spaced pair of arcuate side walls or flanges 55 and 56 having rims 55R and 56R which represent the inside diameter of the assembled disc 50. As in the foregoing embodiment the side walls and their rims 55R and 56R are each of narrower axial dimension in comparison to the teeth 53, and in fact this is true of the combined dimension of the rims accounting for the hollow internal construction to reduce the possible area contact between the disc 50 and its shaft S.

As in the instance of the disc 25, the disc 50 composed of the several segments mentioned above is to be so arranged on the shaft S as to have spacing between the outside diameter of the shaft S and the inner surfaces of the flanges 55 and 56.

In the instance of the disc 25, it will be realized that the disc 25 has some "play" on the shaft S and that in the actual construction each disc 25 will have at least a point of contact with the shaft S. This contact is of no moment, however, insofar as the essential feature of the present invention is concerned which resides in having as little contact as possible between the discs and their shafts. Since, however, the disc 50 is not of one-piece construction, a shim of cardboard 60 or the like is fitted about that portion of the shaft S where a disc 50 is to be mounted. The individual disc segments illustrated in Fig. 8 are then located one-by-one on the shim with the inner rim surfaces of the flanged side walls 55 and 56 in contact with the shim as shown in Figs. 10 and 11, whereupon spaced weldments of spot form, as shown in Fig. 10, are laid down to unite each segment directly to the shaft S as shown in Fig. 10 for rotation therewith. Because the weldments do establish a direct contact between the disc as 50 and its shaft S, such weldments should be held to the minimum necessary to procure a firm and sustainable union.

Still a third form of the present invention is illustrated in Figs. 12 to 15, inclusive. This particular form of the invention in reality embodies some of the features or both of the two embodiments described above. Thus, the chunk breaker disc 70, shown in Fig. 12, is composed of individual segments, but instead of welding these segments directly to the shaft S in the manner described above in connection with Figs. 10 and 11, spacer bars 75, Figs. 14 and 15, are first interposed between the inside diameter of the disc 70, represented by the disc rims 76R and 77R, and the outside diameter of the shaft S on which the discs 70 are mounted to thereby account for a greater degree of radial spacing between the rims of the discs 70 and the related shaft S than is afforded by the modified form of the invention illustrated in Figs. 8 to 11.

Assuming that the teeth on the various different forms of breaker discs under the present invention are all to lie on a common circle, the disc at 70 can in fact be viewed as one wherein the radial dimensions of the side walls 76 and 77 thereof are shortened in comparison to the side walls 55 and 56 of the disc 50. Thus, the side walls 76 and 77 of the disc 70 are of shorter radial dimension than the side walls 55 and 56 of the disc 50, and hence the inner diameter of the disc 70 defined by the radial inner surfaces, 76R and 77R of the side walls 76 and 77 are spaced radially outwardly of the outer diameter

of the shaft S, Figs. 14 and 15, a greater distance than the corresponding spacing in Figs. 10 and 11. In the greater space thus established between the outside diameter of the shaft S and the inside diameter of the disc 70, a plurality of elongated rectangular steel spacer bars 75 are welded at W to the outer diameter of the shaft S in spaced circumferential relation, and the dimension of the parts is such that the internal diameter of the rims afforded by the axially narrowed side walls of the disc 70 are to be radially spaced at ST from the outer surfaces of the spacer bar 75. This spacing can be established by using shims on the outer radial surfaces of the spacer bars in the manner described above.

As in the instance of the disc 50, each disc 70 is constructed from four segments, each having a pair of teeth 79 which are hollow inside diameter of each segment. The segments comprising the disc 70 are dimensioned to establish spacing SP2 between the adjacent ends thereof when the segments are properly assembled in a circle, 20 and as each segment is assembled about the related shaft S weldments W2 are deposited between the ends of the spacer bars 75 and the side walls of the segments to secure the latter to the spacer bars for rotation with the related shaft S.

25 It will be seen from the foregoing that in accordance with the present invention chunk breaker discs, cast from the heat-resistant alloy specified above or one closely akin thereof, are formed to embody spaced arcuate rims of less axial thickness than the thickness of the arcuate outer 30 wall of the disc and the teeth which project from the outer wall. Additionally, the rims of the discs are of larger inside diameter than the outside diameter of the steel shaft on which the discs are to be mounted, and this arrangement and configuration accounts in the first 35 instance for as little contact as possible between the opposed surfaces of the discs and mounting surface of the shaft. In this way, the chances or likelihood of thermal warpage or cracking of the expensive heat-resistant discs, due to the difference in thermal co-efficients between the 40 steel shaft and the discs, is reduced thereby minimizing maintenance problems. It is of course necessary to provide some sort of union between the shaft and the discs in order that the discs will rotate with the shaft, and such union in accordance with the present invention is 45 also of such order as to produce as little contact as possible between the discs and parts in direct contact with the shaft.

Hence, while I have illustrated and described preferred embodiments of my invention it is to be understood that these are capable of variation and modification, and I therefore do not wish to be limited to the precise details set forth, but desire to avail myself of such changes and alterations as fall within the purview of the following claims.

55 I claim:

1. In a chunk breaker to be installed adjacent a furnace for breaking up hot chunks of material discharged from the furnace, a cylindrical supporting shaft adapted to be rotated and cooled internally by means of a fluid cooling stream, said shaft being composed of ferrous material having a given coefficient of thermal expansion, and a breaker disc mounted on said shaft and extending circumferentially thereabout for rotation therewith, said disc being composed of a heat-resistant ferrous metal alloy having a coefficient of thermal expansion different from that of said shaft, said disc having spaced teeth of uniform dimension formed on the outer periphery thereof and having an arcuate inner peripheral rim of narrower axial dimension than said teeth and of greater diameter than the outside diameter of said shaft, and means contacting the outer surface of the shaft at circumferentially spaced points and securing the disc to the outer periphery of said shaft with spacing between the arcuate inner surface of said rim and the outer surface of said shaft.
2. In a chunk breaker to be installed adjacent a fur-

7
nace for breaking up hot chunks of material discharged from the furnace, a supporting shaft adapted to be rotated and cooled internally by means of a fluid cooling stream, said shaft being composed of ferrous material having a given coefficient of thermal expansion, and a breaker disc mounted on said shaft for rotation therewith, said disc being composed of a heat-resistant ferrous metal alloy having a coefficient of thermal expansion different from that of said shaft, said disc having spaced teeth formed on the outer periphery thereof and having an inner peripheral arcuate rim of narrower axial dimension than said teeth, and means contacting the outer surface of the shaft at circumferentially spaced points and securing the disc to the outer periphery of said shaft with spacing between the arcuate inner surface of said rim and the outer surface of said shaft.

3. In a chunk breaker to be installed adjacent a furnace for breaking up hot chunks of material discharged from the furnace, a cylindrical supporting shaft adapted to be rotated and cooled internally by means of a fluid cooling stream, said shaft being composed of ferrous material having a given coefficient of thermal expansion, and a breaker disc mounted on said shaft for rotation therewith, said disc being composed of a heat-resistant ferrous metal alloy having a coefficient of thermal expansion different from that of said shaft, said disc having spaced teeth formed on the outer periphery thereof and having a pair of spaced apart inner peripheral arcuate rims each of narrower axial dimension than said teeth and of larger diameter than the outer diameter of said shaft, and means contacting the outer surface of the shaft at circumferentially spaced points and securing the disc to the outer periphery of said shaft with spacing between the arcuate inner surface of said rim and the outer surface of said shaft.

4. A chunk breaker according to claim 3 wherein the disc is welded at spaced points to the outer surface of the shaft.

5. A chunk breaker according to claim 3 wherein a key is secured to the outer surface of the shaft and the rims of the disc are recessed for receiving the key.

6. A chunk breaker according to claim 3 wherein the disc comprises a plurality of arcuate segments having adjacent ends spaced from one another.

5
10
15
20
25
30
35
40

7. A chunk breaker according to claim 6 wherein spacer bars secured to the outer surface of the shaft are interposed between the rims of the disc and the outer surface of the shaft.

8. A disc adapted to be mounted on a shaft to afford a chunk breaker shaft and comprising an arcuate outer wall having a plurality of radially projecting teeth formed thereon in a single row and in circumferential spaced relation, said teeth each having a given axial thickness and a given radial projecting dimension, and said disc being formed with spaced substantially parallel arcuate side walls affording spaced arcuate inner rims which are concentric to said arcuate outer wall, said rims each being of less axial thickness than the individual axial thickness of said teeth.

9. In a chunk breaker to be installed adjacent a furnace for breaking up hot chunks of material emitting from the furnace, a supporting shaft adapted to be rotated and cooled internally by means of a fluid cooling stream, and a plurality of breaker discs mounted thereon for rotation therewith, said discs each having spaced teeth formed in but a single circumferential row about the outer periphery thereof and each having an inner peripheral rim of narrower axial dimension than said teeth, and means securing each disc to the outer periphery of said shaft to provide heat barrier spacing between the arcuate inner surface of each rim and the outer surface of said shaft, said securing means contacting the outer surface of the shaft discontinuously at widely spaced points circumferentially about the outer surface of said shaft and contacting each of said discs discontinuously and only at widely spaced points.
